UNITED STATES PATENT OFFICE.

JOHN W. HANLEY, OF NEW YORK, N. Y.

DESIGN FOR A CUP OR SIMILAR ARTICLE.

SPECIFICATION forming part of Design No. 29,617, dated November 8, 1898.

Application filed September 28, 1898. Serial No. 692,138. Term of patent 7 years.

To all whom it may concern:

Be it known that I, JOHN WILLIAM HANLEY, a citizen of the United States, residing at the city of New York, borough of Manhattan, in the county and State of New York, have invented and produced a new and original Design for a Cup or Similar Article, of which the following is a specification, reference being had to the accompanying drawings, forming a part thereof, in which—

Figure 1 is a plan view of a cup embodying the features of my design. Fig. 2 is a side elevation of the cup, and Fig. 3 is a transverse section taken practically on the line 3—3 of Fig. 1.

The design relates particularly to such articles as tea or coffee cups, tumblers, &c. A circle appears in the bottom of the vessel, divided into sections *a*, and a representation of the sun, *B*, is located at the center of the said

circle. The inner side surface of the vessel is decorated with panels *C*, formed by the intersection of vertical lines *c* with circular horizontally-located lines *c'*, and in sundry of the panels pictorial figures *D* appear. Externally the vessel is decorated with a series of panels *E*, which panels correspond in location to the series of longitudinal interior panels.

The leading feature of the design consists in a cup or similar article internally decorated with a bottom panel and series of side panels grouped around the bottom panel.

I claim—

The design for a cup or similar article herein shown and described.

JOHN W. HANLEY.
